(57) **CLAIM**

The ornamental design for a display panel portion with an animated icon, as shown and described.

DESCRIPTION

FIG. 1 is a first image in a sequence for a display panel portion with an animated icon, showing our new design. FIG. 2 is a second image in the sequence thereof.

FIG. 3 is a third image in the sequence thereof; and, FIG. 4 is a fourth image in the sequence thereof.

The appearance of the animated icon sequentially transitions between the images shown in FIGS. 1-4. The process or period in which one image transitions to another image forms no part of the claimed design.

The broken lines showing a display panel portion and portions of the animated icon in FIGS. 1-4 form no part of the claimed design.
